JOSEPH CORDNAN, OF BROOKLYN, NEW YORK, ASSIGNOR TO HIMSELF AND R. W. POTTER, OF SAME PLACE.

Letters Patent No. 76,166, dated March 31, 1868; antedated March 17, 1868.

FLUID-INDICATOR.

The Schedule referred to in these Letters Patent and making part of the same.

TO ALL WHOM IT MAY CONCERN:

Be it known that I, JOSEPH CORDNAN, of the city of Brooklyn, in the State of New York, have invented certain new and useful Improvements in Fluid-Indicators; and do hereby declare the following to be a full, clear, and exact description of the same, reference being had to the accompanying drawings, and to the figures and letters marked thereon. Of these drawings—

Figure 1 is a longitudinal central section of the indicator.

Figure 2 is a plan view.

Figure 3 is a plan view of the top of the registering-mechanism.

Figure 4 is a bottom view of the registering-mechanism; and

Figure 5, an internal plan view with the registering-mechanism removed.

Similar letters of reference indicate corresponding parts in the several figures.

In my improved fluid-indicator there is an exterior vessel, of a conical shape, containing a screw with spiral blades which taper towards the apex or narrowest part of such vessel. The fluid acting on such spiral blades, produces a centripetal action, thereby overcoming the great wear of the centres, and obviating the consequent defective operation of indicators as heretofore constructed.

The mechanism for registering the flow of the fluid is placed within and at the base of this cone-shaped vessel, and arranged around the spindle containing the spiral tapering blades, and constructed with a series of worms or endless screws and cog-wheels, so as to give compactness, avoid packing of joints, and have a continuous screw-mechanism throughout. This arrangement of the blades and registering-mechanism is intended to secure the greatest power with the least friction.

In order to further overcome friction, and consequent wear of parts, I propose to make the centres or bearings of the spindle, containing the radial tapering blades, of a compound of copper and tin, and which will run into recesses, in the ends of the spindle, composed of or faced with horn, the water acting on the same as a lubricator.

In the accompanying drawings, *a* represents the conical-shaped vessel; *b*, a spindle, constructed with spiral radial blades, (I have found that with three there is obtained a perfect working,) *c c*, set at a varying angle, and with a curvature on the outer extremities of each blade, to conform with the inner periphery of the conical vessel. In the apex or narrowest part of the vessel is the eduction-aperture, and within it is placed an arm, *d*, which contains a centre or bearing, *e*, which passes into the recess *f* of the spindle *b*, such recess being composed of or lined with horn. The upper end of this spindle finds a bearing on a pivot placed in an arm, *g*, just within the induction-aperture, where the horn recess is also used. At some distance along the spindle *b* is placed a worm or endless screw, *h*, which gears with the registering-mechanism attached to the plate *i*, and around the said spindle. This mechanism can be inserted within the body of the indicator, or removed therefrom at pleasure, being held in place by the arms *j j j*.

The registering-mechanism is arranged with the worms 1 2 3 and cog-wheels 4, 5, 6, and 7, in connection with the index-wheels, &c., so as to register two gallons, (or cubic feet, if required,) and multiples of this number, in a compact manner, with less gear than generally used. I prefer that shown, though this registering-mechanism can be constructed in many different ways. In the one I have shown there is certainty of movement. Solid matter in the fluid is not liable to affect its operation, and every index in the train is locked and motionless, except by the movement of the screw.

k is a solid piece of glass, which I prefer to be slightly convex, placed in a suitable frame, through the centre of which passes the induction-aperture before referred to. This plate or piece of glass is held down by the rim *l* pressing on to it, and screwing into the body of the vessel. A piece of rubber is interposed between the glass and vessel, that is, placed on a shoulder in the vessel at *m*, on to which presses the frame containing the glass, and thus affords a good packing, but any other convenient way of packing may be adopted. At a point in the induction-pipe just before the fluid passes into the vessel, I place a wire screen, *n*, so as to prevent solid substances from passing through the indicator. At a point in the eduction-pipe, and just outside of the

vessel, I place another screen, *o*, so that the circular motion of the fluid received by passing on to the radial blades may be broken, and to assist the fluid in moving along again in a right line. Instead of having the induction-aperture at the centre of the plate or piece of glass, it may be placed at the side, as shown in figs. 1, 2, and 5, in red lines, and thereby permit of a wholly unobstructed view of the indexes of the registering-mechanism.

This indicator will measure fluids with the utmost nicety under any head or pressure of water, as has been demonstrated by actual tests, and will not, in use, become defective by reason of the rapid wear of centres, as is the case with registers heretofore constructed, the overcoming of this difficulty being due to the centripetal principle upon which my register operates, and the screw and registering-mechanism being, as before stated, constructed in one continuous screw.

Having described my indicator, what I claim as new, and desire to secure by Letters Patent, is—

1. A screw composed of blades, of a spiral tapering form, in combination with a conical-shaped vessel or surface adapted to such screw, and a registering-mechanism, substantially as and for the purpose herein described.
2. The employment, in the ends of the spindle of said screw, of horned recesses, substantially as and for the purpose described.
3. The arrangement of the registering-mechanism around the spindle of the screw, and within the body of the indicator, substantially as and for the purpose described.
4. The construction of the registering-mechanism, substantially as described, so as to form an endless screw throughout, and thereby overcome friction and increase the facility of the indicator to register.
5. The arrangement of gauze-wire work within the induction-aperture, substantially as described, in order to prevent substances from passing into the indicator.
6. The arrangement of gauze-wire work within the induction-aperture, so as to destroy the circular motion that the fluid receives in passing through the indicator.

JOSEPH CORDNAN.
